UNITED STATES PATENT OFFICE

171,479

ESCUTCHEON PLATE

Henry R. Bassaraba, Chicago, Ill., assignor to The
Merit Company, a corporation of Illinois

Application June 25, 1953, Serial No. 25,660

Term of patent 14 years

(Cl. D13—1)

To all whom it may concern:

Be it known that I, Henry R. Bassaraba, a citizen of the United States, residing in Chicago, in the county of Cook and State of Illinois, have invented a new, original, and ornamental Design for an Escutcheon Plate, of which the following is a specification, reference being had to the accompanying drawing, forming part thereof.

Figure 1 is a front elevational view of an escutcheon plate embodying my new design;

Figure 2 is a top plan view thereof; and

Figure 3 is an end elevational view thereof.

I claim:

The ornamental design for an escutcheon plate, as shown.

HENRY R. BASSARABA.
